FINGER RING

Benjamin Axel, Long Island City, N. Y., assignor
to Axel Bros., Inc., Long Island City, N. Y., a
corporation of New York

Application July 7, 1950, Serial No. 10,998

Term of patent 14 years

(Cl. D45—10)

To all whom it may concern:

Be it known that I, Benjamin Axel, a citizen of the United States and a resident of Long Island City, county of Queens, State of New York, have invented a new, original, and ornamental Design for a Finger Ring, of which the following is a specification, reference being had to the accompanying drawing, forming a part hereof, in which:

Figure 1 is a top plan view of the setting element of the finger ring illustrated in Figure 4;

Figure 2 is a view similar to Figure 1 with a gem illustrated in broken lines;

Figure 3 is a front elevational view of a finger ring embodying my new design with the gem omitted; and

Figure 4 is a side elevational view of the finger ring.

The dominant features of my design reside in the setting element shown in full lines.

I claim:

The ornamental design for a finger ring, substantially as shown and described.

BENJAMIN AXEL.
